ELECTRICALLY OPERATED TIMING DEVICE

Charles Fayer, Flushing, N. Y., assignor to
Wappler Electric Company, Inc., a corporation
of New York

Application April 1, 1931, Serial No. 526,960

6 Claims. (Cl. 250—34)

My invention relates to timing devices and more particularly to a timing device arranged to initiate a plurality of operations in rapid succession and in the proper sequence.

While my timing device is capable of a wide variety of uses it is particularly adapted for utilization with X-ray apparatus. In apparatus of this character it is frequently desirable to make a series of radiographic exposures of some particular portion of the human anatomy. These exposures must usually be made in rapid succession before the organ, which is being radiographed, alters its position in performing its natural function. It is sometimes more desirable to radiograph the organ from two or more distinct angles in order that the resulting radiographic exposures may be studied stereoscopically.

In either of these events it is desirable that the period of exposure of the sensitized film to the X-rays be of the proper duration and that the second exposure follow as expeditiously as possible, and also that the film be exposed to the X-rays for the proper period of time to give a clear and distinct picture.

The desirability of having a device which is accurate and dependable for properly timing the various exposures of the films, the rapid changing of the exposed film out of position and the unexposed film into position, and the changing of the angle of the tube or film for a stereoscopic exposure, thus becomes manifested. Timing devices, as known to the prior art, have been limited in the scope of operations which they can perform and have been as a whole inaccurate and unreliable.

It is, therefore, an object of my invention to provide a timing device which is accurate and dependable for initiating the operation of a plurality of functions in rapid succession and in the proper sequence.

Another object of my invention is the provision of a timing device for initiating the energization of an X-ray tube, the shifting of the sensitized film and the changing of the angle of the X-ray tube and film relative to each other if desired.

A further object of my invention is the provision of a timing device which initiates the operation of various parts of an X-ray apparatus with great rapidity in a predetermined sequence and in which the timing device is adjustable within certain limits for altering the time of operation of a portion of the apparatus.

Still further objects of my invention will become apparent to those skilled in the art by reference to the accompanying drawings wherein:

Fig. 1 is a plan view of my timing device with a portion of the apparatus broken away to better illustrate the mechanism and showing an electrical circuit with which my device may be readily utilized.

Fig. 2 is a front elevational view of my timing device on a smaller scale showing various time settings of the device;

Fig. 3 is a rear elevational view partly in section taken on the line III—III of Fig. 1;

Fig. 4 is a cross-section taken on the line IV—IV of Fig. 3 showing an engaged position of a portion of the device;

Fig. 5 is a cross sectional view similar to Fig. 4 but showing the disengaged position of a portion of the device;

Fig. 6 is a cross sectional view taken on the line VI—VI of Fig. 4 showing the method of locking the device in the various time setting operations.

Referring to the drawings in detail I have shown in the several figures a base member 5, preferably of a light metal, upon which is mounted a constant speed synchronous motor 6. A pair of upstanding lugs 7 and 8 are secured to the base member and are provided with bearing portions 9 and 10. A coarsely threaded worm shaft 11 is journaled in the bearing portions of the lugs 7 and 8 and is connected to the motor 6, by means of a conventional coupling 12, and the worm shaft is provided with an unthreaded portion 13, near one extremity, of smaller diameter than the diameter of the remaining portion of the shaft. Another pair of upstanding lugs 14 and 15 are secured to the base and are provided with suitable bearing portions 16 and 17 and a shaft 18 is journaled in these bearing portions and extends slightly beyond these lugs.

A pair of brackets 19 and 20 are rigidly secured to the ends of the shaft 18 and a square shaft 21 is rigidly secured to these bracket members 19 and 20. A member 22, provided with an arcuate face having threads of the same size and pitch as the threads of the worm shaft 11 is adapted to engage this worm shaft and move longitudinally of the worm shaft 11 upon the square shaft 21. This member 22 is provided with a laterally extending portion 23 and has secured to its upper face a small block of insulating material 24. A spring contact member 25 of substantially U-shaped configuration is secured to this insulating block and thus moves with the member 22.

A pair of bracket members 26 are secured to the base member 5 and a spring reel 27 is jour-

naled between these bracket members. A small chain or cable 28 extends from this spring reel and is secured to the laterally extending portion 23 of the member 22. An angular bracket 29 is secured to the base member 5 and supports a solenoid 30. A plunger 32 of the solenoid is provided with a portion 33 which acts as a counter-weight and an arm 34, provided with a forked portion 35, engages the plunger of the solenoid and is rigidly secured to the shaft 18 for the purpose of rocking the shaft 18 and the brackets 19 and 20, to cause engagement of the member 22 with the worm shaft 11.

A plate 36 of suitable insulating material, such as bakelite or a phenolic condensation product is mounted on the top of the lugs 7 and 8 and assists in supporting a pair of panels 37 and 38 which are also secured to the base member. A pair of lugs 39 and 40 extend upwardly from this plate and a shaft 42 is journaled in these lugs. A control knob 43 is rigidly secured to one end of the shaft 42 which extends through the front of the panel 37. The other end of this shaft has rigidly secured thereto an insulating block 44 and secured to the vertical faces of this block 44 are a pair of contact members 45 and 46. These contact members are notched, forming contact surfaces of varying length and when the shaft 42 is rotated by the control knob 43 these contact surfaces of varying length are positioned to be contacted by the spring contact 25 carried by the movable member 22. The shaft 42 is further provided with a square section 47 disposed between the lugs 39 and 40 and a spring 48 is secured to the lug 39 and arranged to contact a surface of this square portion 47 for maintaining the contact members 45 and 46 in their desired position.

Another pair of lugs 49 and 50 are secured to the plate 36 and a shaft 52 is journaled in these lugs. This shaft 52 is likewise provided with a control knob 53 at one of its ends and an insulating block 54. The block 54 is provided with contact members 55 and 56 similar to the contact members 45 and 46 likewise positioned to be engaged by the spring contact 25 carried by the movable member 22. This shaft is also provided with a square portion 57 and a spring 58 is arranged to contact the square surfaces of the portion of the shaft 57 in the same manner as the spring 48.

The panels 37 and 38 are provided with graduations indicating fractions of a second and rotation of the control knobs 43 or 53 to the desired graduation rotates the contact members 45, 46 and 55, 56 respectively and thus varies the length of the contact surfaces of these members positioned to be contacted by the member 22 and spring contact 25 during their movement longitudinally of the shaft 11.

A pair of spring contact members 59 and 60 are secured to a lug 62, secured to the plate 36, and are arranged to engage the contact members 45 and 46 and to be thus in electrical connection with these members at all positions of the latter when rotated by the control knob 43. A similar pair of spring contact members 63 and 64 are likewise mounted upon the lug 65, also secured to the plate 36, and are arranged to be in electrical conductive communication with the contact members 55 and 56. Another pair of contact members 66 and 67 are mounted upon the plate 36 and positioned in the line of travel of the member 22 in back of the contact members 45 and 46.

A similar pair of contact members 68 and 69 are likewise mounted on the plate 36 in back of the contact members 55 and 56. Movement of the member 22 will thus first establish contact between the contact members 45 and 46, then the contact members 66 and 67, after which connection is established between the contact members 55, 56 and 68, 69.

The period of time in which connection will be established between the contact members 45, 46 and 55, 56 respectively will depend upon the length of the surface of these respective contact members which are engaged by the contact member 25, carried by the member 22. The length of the engaged surface of the members becomes less with each graduation as marked on the panels 37 and 38, thus varying the time that the contact member 25 is in engagement with these members.

Upon energization of the solenoid 30 the plunger 32 is drawn upwardly thus moving the arm 34 and slightly rotating the shaft 18, to which it is secured, in the bearing portions 16 and 17. The brackets 19 and 20 being secured to the shaft 18 are likewise moved and cause movement of the square shaft 21 thus engaging the member 22 with the worm shaft 11. Rotation of the worm shaft 11 will thus cause longitudinal movement of the member 22 due to the threaded engagement and the contact member 25 carried by this member will contact the various contact members during its movement in the aforementioned manner until the member 22 has traveled its full length, at which time, it will have passed beyond the threaded portion to the portion 13 of smaller diameter. The member 22 will remain adjacent this portion as long as the solenoid 30 remains energized as the threads of the worm shaft 11 prevent the spring reel 27 from becoming effective to retract the member 22. Upon de-energization of the solenoid 30 the member 22 will, however, immediately be retracted to the other extremity of the square shaft 21 or its starting position by the spring reel 27 and the chain or cable 28.

The member 22 in its movement thus establishes contact between a plurality of contact members which may be utilized to operate any desired apparatus.

As an illustration of a type of apparatus with which my timing device may be readily utilized I have shown in Figure 1 an X-ray apparatus in which it is desirable to perform a plurality of functions with great rapidity and in their proper sequence. I have shown a pair of conductors L1 and L2 which represent a suitable source of commercial alternating current potential.

A pair of conductors 100 and 102 extend from this source to a junction 103 and 104 respectively. Conductors 105 and 106 extend from these junctions to the motor 6 and conductor 107, extends from the junction 103, to a junction 108, thence to a junction 109, and from the latter to one end of the winding of the solenoid 30.

A conductor 111 extends from the junction 104 to a switch S1 and from this switch a conductor 112 extends to the other end of the winding of the solenoid 30. A switch S2 is interposed between the conductor 100 and the supply conductor L1 for the purpose of energizing the motor 6 and placing the timing device in position for operation. The switch S1 completes the circuit to the solenoid for the purpose of causing engagement of the member 22 with the worm shaft 11 as aforementioned.

A conductor 113 extends from the junction 108 to the spring contact member 59 which is in en-

gagement with the contact member 45 and a conductor 114 extends from the junction 109 to the contact member 66. A conductor 115 extends from the contact member 60, which is in engagement with the contact member 46, to a junction 116 and from this latter junction a conductor extends through the coil of a relay R1 to the conductor 102, which is connected to the supply conductor L2.

10 Another conductor 117 extends from the junction 116 to one end of the winding of a relay R2. A conductor 118 extends directly from contact member 67 to one end of a winding of a relay R3. A conductor 119 is connected to the supply conductor L2 and extends to one end of the primary winding of a high tension transformer T1, thence to one end of the primary winding of a low-tension transformer T2 and from this point to the other end of relays R2 and R3. A conductor 120 is connected to conductor 100 and extends to a junction 122, from this junction a conductor 123 extends to a contact terminal of an oil immersed switch 121 which is actuated by the relay R1.

25 A conductor 124 also extends from the junction 122 to a switch S3 and from this switch to a variable resistance R. A conductor interconnects the variable resistance and the other end of the primary winding of the low-tension transformer T2. Closure of the switch S3, after closing of switch S2, thus energizes the primary winding of the low tension transformer T2. A conductor 125 extends from the remaining end of the primary winding of the high tension transformer T1 to the other contactor of the oil immersed switch 121. The secondary winding of high-tension transformer T1 supplies high potential current to an X-ray tube 126 while the secondary winding of low-tension transformer 40 T2, supplies heating current for the filament of the X-ray tube in the usual manner.

The solenoid 127 is connected across the conductors 118 and 119 and is thus electrically in shunt relation with the relay R3 to cause the shifting of the X-ray tube 126 simultaneously with the movement of one of the films out of position and the other of the films into position for a radiographic exposure. The shifting of the X-ray tube changes the relative angle between the tube and film a distance corresponding to the average interpupillary distance in order that the resulting pictures may be taken from two distinct angles for the purposes of stereoscopic study. This being a well known expedient in the art with various types of mechanism being employed for accom-

plishing the shifting of the tube it is believed to be unnecessary to describe in detail any specific mechanism. I have accordingly shown the plunger of solenoid 127 loosely connected to one end of a pivoted arm 127' with the other end of this arm slidably engaging a suitable ring or collar which surrounds the X-ray tube. Movement of the plunger of solenoid 127 will, therefore, cause a corresponding shifting of the X-ray tube 126.

65 The spring contact members 63 and 64, which are electrically connected to the contact members 55 and 56, are connected with a pair of conductors 128 and 129 which may extend to the junction 108 and to the conductor 115, as shown in dotted lines, for again actuating the relay R1 of the oil immersed switch and the relay R2, if desired, or these conductors may be connected to other apparatus for performing any other desired functions in a like manner. A pair of conductors 70 132 and 133 are connected to the contact mem-

bers 68 and 69 and may likewise extend to other apparatus.

The operation of my timing device may be best understood by assuming a given problem. Assuming it is desired to utilize my timing device with X-ray apparatus in which a plurality of radiographic exposures are desired, with one exposure following the other with great rapidity, or a plurality of radiographic exposures are desired in which the relative angle between the X-ray tube and the sensitized film is to be changed with each exposure in order to permit the resulting pictures to be viewed stereoscopically, the operation of my apparatus may be described as follows:

80 The switch S2 is first closed allowing the electrical energy to flow from the source of supply L1 and L2 by means of the conductors 100 and 102 to the motor 6. The motor will then rotate the worm shaft 11 in the direction indicated by the arrow in Figure 1. The control knobs 43 and 53 may then be set to the graduation desired and as indicated, for the period of time desired, on the panels 37 and 38. The switch S3 is next closed to energize the low-tension heating transformer T2 to heat the cathode of the X-ray tube 126 and 85 the variable resistance R adjusted for the desired amount of current.

90 This circuit may be traced from the conductor 100 through conductor 120, junction 122, then by means of conductor 124, switch S3, variable resistance R, the primary winding of transformer T2, and thence by means of conductor 119 to the supply conductor L2. The secondary winding of the transformer T2 is thus energized and the cathode of the X-ray tube heated to a thermionic 100 electron emitting temperature.

95 The switch S1 is then closed thus energizing the winding of the solenoid 30. A circuit is then completed to the motor and the solenoid 30 which may be traced from the source L1 through switch S2, conductor 100, to junction 103, from junction 103 to the motor, thence by means of conductor 105, junction 104, and conductor 102, back to supply conductor L2. A circuit to the relay may be traced from the junction 103, by means of a conductor 107, through junction 108 and 109, to the winding of relay 30, thence by means of conductor 112, switch S1, and conductor 111 to the junction 104. Energization of the solenoid 30 raises the plunger 32 and rotates the shaft 18 allowing the 110 member 22 to engage the threaded portion of the worm shaft 11. As the worm shaft 11 is now being rotated by the motor the engagement of the member 22 and the worm 11 causes the member 22 to travel longitudinally of the square shaft 21.

115 The spring contact member 25 which is of substantially U shaped configuration and is secured to the member 22 first engages the contact members 45 and 46 in its movement longitudinally of the shaft 21. This bridges the contact members 120 45 and 46 and completes a circuit to the coil of relay R1 of the oil immersed switch and to the coil of relay R2, which is herein shown as being employed as a relay for pressing the film against the cassette tray.

125 A circuit may be traced from the junction 108, which is now supplied with energy, through the conductor 113, spring contact member 59, contact member 45, through the U-shaped contact member 25 to the contact member 46, thence through 130 spring contact member 60, conductor 115 to junction 116, and then through the winding of relay R1 to conductor 102 which is supplied with current from the source L2. The oil immersed switch 135 then closes its contact members and completes 140 145 150

the circuit to the primary winding of high tension transformer T1 which in turn energizes the secondary winding and the X-ray tube 126.

This latter circuit may be traced from the conductor 100 by means of conductor 120 to the junction 122, through conductor 123, through the oil immersed switch and conductor 125, through the primary winding of high tension transformer T1 to the conductor 119 and thence to the supply conductor L2.

At the same time that the relay R1 is energized the relay R2 is likewise energized. This circuit may be traced from the junction 116, which is now carrying electrical energy, through conductor 117, the winding of relay R2 to the conductor 119 and back to the supply conductor L2 as just described. The closing of the oil immersed switch energizes the X-ray tube and the first exposure of the object of the X-radiation is thus registered upon the first film.

The period of time of the energization of the X-ray tube will depend upon the length of the surface of the contact members 45 and 46 which were preset to give the period desired, and which are engaged for this predetermined period by the contact 25 carried by the member 22.

Further longitudinal movement of the member 22 causes the contact member 25 carried thereby to break the connection between the members 45 and 46, and upon further movement to establish connection between the contact members 66 and 67. The bridging of these contact members 66 and 67 completes a circuit to the relay R3 which is here shown for the purpose of shifting the exposed film out of position and the unexposed film into position.

The relay or solenoid 127 is energized simultaneously with the relay R3 for the purpose of shifting the X-ray tube to alter the relative angle between the tube and films to correspond to the usual interpupillary distance by any of the well-known methods employed in the art. In the drawings I have shown the plunger of solenoid 127 as moving downwardly (Fig. 2) in response to energization of its winding with attendant upward movement of the X-ray tube 126. Upon de-energization of the solenoid 127 the weight of X-ray tube 126 and its associated parts causes the plunger to be returned to its normal or upward position. Although I have shown the tube as being shiftable to change the relative angle between the tube and films it is to be understood that the film holder or cassette may be tilted in lieu of the tube to change the angle.

This circuit extends from the junction 109, which is now energized, through conductor 114, contact member 66, through contact member 25 carried by the member 22 to contact member 67, then by means of conductor 118 to the winding of relay R3, and thence by means of conductor 119 to supply conductor L2. This trips the mechanism and allows the exposed film to move out of position and the unexposed film to move into position at the same time the solenoid 127 is energized, as it is connected across the conductors 118 and 119 which are now energized.

This relay is utilized to cause movement of the X-ray tube or shifting of the film to enable a picture of the object to be taken from a different angle, as hereinbefore explained. Further movement of the member 22 longitudinally of the shaft 21 will disengage the contact members 66 and 67 and thus de-energize the relays R3 and solenoid 127, and then to establish connection between the

contact members 55 and 56 to again energize the X-ray tube in the manner as just described.

Should these contact members be employed for this purpose the spring contact members 63 and 64 would be connected by means of conductors 128 and 129 to the conductor 115 and junction 108 as shown in dotted lines. They may, however, be connected to other portions of the apparatus in which it is desired to perform other operations.

Upon further movement of the member 22 the contact member 25 will disengage the contact members 55 and 56 and next establish connection with the contact members 68 and 69 and thus enable the circuit for the actuating of the apparatus by means of conductors 132 and 133, if desired, in the same manner as the bridging of the contact members 66 and 67 as previously described.

The member 22 in travel further on the shaft 21 will then disengage the contact members 68 and 69 and move along the shafts 11 and 21 until the member 22 has reached its limit of travel. When the member has reached its limit of travel it will be adjacent the unthreaded portion 13 of the worm shaft which is of smaller diameter and thus no longer engages the arcuate threaded portion 100 of the member 22. This member will, therefore, remain in this position until the switch S1 or S2 is open to de-energize the solenoid 30.

Upon de-energization of the solenoid 30 the member 22 will be retracted to the other end of the square shaft 21 by means of the spring reel 27 and the chain or cable 28. A suitable bumper, of felt or rubber, 128' may be provided for absorbing the shock attendant the retraction of this member. A similar bumper 129' may be provided beneath the plunger 32 of the solenoid 30 to likewise absorb the shock of this weighted member upon de-energization of the solenoid.

The contact members 45, 46 and 55, 56 which have surfaces that vary in length corresponding to the period of time as indicated on the panels 37 and 38 are maintained in the desired setting by means of the respective springs 48 and 58 which engage the square portion 47, 57 of the shafts 42, 52 respectively.

It can thus be readily seen that I have provided a timing device which is accurate and dependable and which is capable of initiating the operation of a plurality of operations with great rapidity and in the proper sequence. Furthermore the periods of operation of a portion of the apparatus may be readily adjusted as desired to give varying periods of operation. It is to be understood that although I have shown a substantially square shaft allowing only four graduations of time, ranging from approximately one-twentieth to one-fifth of a second, my timing device may be just as readily employed to give various other graduations by employing a hexagonal or an octagonal section in the respective shafts 42 and 52 and by providing additional sections on the contact members 45, 46 and 55, 56 respectively.

Although I have shown and described a specific embodiment of my invention I do not desire to be limited thereon as various other modifications of the same may be made without departing from the spirit and scope of the invention as set forth in the following claims.

What is claimed is:

1. In an X-ray system, the combination with an X-ray tube and a plurality of sensitized films, of a timing device for causing a plurality of operations in a predetermined sequence comprising an electric motor, mechanism operated by said motor, a plurality of contact members disposed ad-

- jacent said mechanism, a plurality of circuits each including some of said contact members, a movable member operable by said mechanism for engaging each of said contact members in succession and for a predetermined time during its movement to complete each of said circuits and cause energization of said X-ray tube, the changing of the angle of said X-ray tube relative to said sensitized films and the simultaneous shifting of one of said films out of position and another of said films into position for a radiographic exposure, and the reenergization of said X-ray tube, respectively in sequence, adjustable means carried by said mechanism for varying the period of time said movable member engages some of said contact members to cause a corresponding variation in the time period of energization of said X-ray tube, and means responsive to actuation by an operator for initiating the operation of said movable member. 80
2. In an X-ray system, the combination with an X-ray tube and a plurality of sensitized films, of a timing device for causing a plurality of operations in a predetermined sequence comprising an electric motor, mechanism operable by said motor, a plurality of contact members disposed adjacent said mechanism, a partially completed electrical circuit including some of said contact members for causing energization of said X-ray tube from a suitable source of electrical energy, a second partially completed electrical circuit including some of said contact members in addition to those included in said first mentioned circuit, a suitable source of energy, and means energizable by the latter for changing the angle of said X-ray tube relative to said sensitized films and for simultaneously shifting one of said films out of position and another one of said films into position for a radiographic exposure; a movable member included in said mechanism and operable to engage each of said contact members during its movement to complete and interrupt said first mentioned circuit, said second mentioned circuit, and again complete and interrupt said first mentioned circuit in succession, means carried by said mechanism for adjusting said contact members included in said first mentioned circuit for varying the period of energization of said X-ray tube, and means responsive to actuation by an operator for initiating the operation of said movable member by said electric motor and mechanism. 95
3. In an X-ray system, the combination with an X-ray tube and a plurality of sensitized films of a timing device comprising a motor energizable from a suitable source of electrical energy, mechanism operable by said motor for completing a circuit from a suitable source of energy to said X-ray tube for a predetermined period of time, means operable by said mechanism for causing the changing of the relative angle between said X-ray tube and said film and for simultaneously causing one of said films to be moved out of position and another of said films into position for a radiographic exposure, means operable by said mechanism to again energize said X-ray tube following the changing of the angle of said X-ray tube and the shifting of said films to expose another of said films to said X-ray tube, and means associated with said mechanism and electrically responsive to actuation by an operator for initiating operation of said mechanism. 100
4. In an X-ray system, the combination with an X-ray tube and a plurality of sensitized films, 105
- of a timing device comprising a motor energizable from a suitable source of electrical energy, mechanism operable by said motor, a plurality of contact members disposed adjacent said mechanism, means electrically connected to some of said contact members and operable to energize said X-ray tube, means electrically connected to other of said contact members and operable to cause the changing of the relative angle between said X-ray tube and said films and for simultaneously shifting one of said films out of position and another of said films into position for a radiographic exposure, a movable member included in said mechanism and operable to establish a connection with all of said contact members in succession during its movement, to cause the operation of said first mentioned means for a predetermined period of time, operation of said second mentioned means, and again cause operation of said first mentioned means for a predetermined period of time, in sequence; and means responsive to actuation by an operator for initiating the movement of said movable member, and said movable member being retractable to its initial position upon said last mentioned means being rendered inoperative by the operator. 110
5. In an X-ray system, the combination with an X-ray tube and a plurality of sensitized films, of a timing device for causing a plurality of operations for a predetermined period of time and in a predetermined sequence comprising an electric motor energizable from a suitable source of electrical energy, a worm shaft driven by said motor, a plurality of contact members disposed adjacent said shaft, a partially completed circuit including some of said contact members and adapted upon completion thereof to initially energize said X-ray tube, a second partially completed circuit including other of said contact members and adapted upon completion thereof to cause the changing of the relative angle between said X-ray tube and said films following initial energization and deenergization of said X-ray tube, a third partially completed circuit including the same contact members as said second mentioned circuit and adapted upon completion thereof to cause the shifting of one of said films out of position and the other of said films into position for a radiographic exposure simultaneously with the changing of the angle between said X-ray tube and said films, a fourth partially completed circuit including still other of said contact members and adapted upon completion thereof to again energize said X-ray tube 115
- subsequent to the shifting of said films and the changing of the relative angle between said X-ray tube and said films, a shaft carried by a pair of rockable brackets disposed adjacent said worm shaft, a movable member carried by said shaft 120
- operable to establish a connection with the contact members of each respective circuit in succession to complete each of said circuits and cause the operation thereof in their respective sequence during its movement, said movable member being provided with a threaded portion corresponding to said worm shaft and arranged to engage the latter and to be driven thereby longitudinally of said second mentioned shaft, and a solenoid responsive to actuation by an operator for rocking the brackets supporting said second mentioned shaft to cause said movable member to engage said worm shaft. 125
6. In an X-ray system, the combination with an X-ray tube and a plurality of sensitized films, 130
- 135
- 140
- 145
- 150

of a timing device for causing a plurality of operations for a predetermined period of time and in a predetermined sequence comprising an electric motor energizable from a suitable source of electrical energy, a worm shaft driven by said motor, a plurality of contact members disposed adjacent said shaft with a portion thereof having contact surfaces of varying length and a control knob for presetting said contact members to the desired contact surface corresponding to a predetermined time period, a partially completed circuit including some of said contact members having surfaces of varying length and adapted to be initially completed to cause the energization of said X-ray tube, a second partially completed circuit including other of said contact members and adapted to be completed following initial energization and deenergization of said X-ray tube to cause the changing of the relative angle between said X-ray tube and said films, a third partially completed circuit including the same contact members as said second mentioned circuit and adapted upon completion thereof to cause the shifting of one of said films out of position and the other of said films into position for a radiographic exposure simultaneously with the changing of the angle between said X-ray tube and said films, a fourth partially completed circuit including other of said contact members having surfaces of varying length and adapted to be completed subsequent to the shifting of said films and the changing of the angle between said X-ray tube and said films to again energize said X-ray tube, a shaft carrying a movable member disposed adjacent said worm shaft, said movable member being provided with a threaded portion corresponding to that of said worm shaft and adapted to engage the latter to cause movement of said movable member longitudinally of said second mentioned shaft, and said movable member being operable to establish a connection with the contact members of each respective circuit in succession to complete each of said circuits and cause the operation thereof in their respective sequence during its movement, a solenoid energizable in response to actuation by an operator to cause engagement of said movable member with said worm shaft, and said movable member being automatically retractable to its initial position in response to the deenergization of said solenoid by the operator.
